UNITED STATES PATENT OFFICE.

HERMAN G. FARR, OF SPRINGFIELD, MASSACHUSETTS.

DESIGN FOR AN AUTOMOBILE FIRE-ENGINE BODY.

45,416.

Specification for Design.

Patented Mar. 17, 1914.

Application filed January 17, 1914. Serial No. 812,854. Term of patent 14 years.

To all whom it may concern:

Be it known that I, HERMAN G. FARR, a citizen of the United States, residing at Springfield, in the county of Hampden, in the State of Massachusetts, have invented a new, original, and ornamental Design for Automobile Fire-Engine Bodies, of which the following is a specification, reference being had to the accompanying drawing, forming part thereof.

The figure is an elevation of an automobile fire engine body showing my new design.

I claim;

The ornamental design for automobile fire engine body, as shown.

HERMAN G. FARR.

Witnesses:

H. E. HARTWELL,

F. G. NEAL.
